UNITED STATES PATENT OFFICE.

RALPH WILLIS LIVINGSTON, OF HOLLOWAY, OHIO.

PIPE BRACE AND HANGER.

Application filed March 10, 1927. Serial No. 174,312.

The invention relates to pipe braces and hangers particularly adapted for use in connection with stove pipe L's, and has for its object to provide a device of this character which may be anchored to the ceiling and having outwardly extending looped members adapted to encircle portions of the L's for bracing said portions, and the device as a whole rigidly holding the stove pipe L's in position at all times, thereby allowing a stove to be disconnected from the stove pipe without breaking the connection of the pipe with a ceiling or other discharge opening.

A further object is to provide a downwardly extending hanger bar connected to the ceiling and having a loop connection with the horizontal portions of the stove pipe L's and horizontally disposed members carried by the bar and encircling the vertical portions of the L's for rigidly bracing the L's, and maintaining the same at all times in a relative relation to the ceiling. Also to provide elongated bolt receiving apertures, thereby allowing a range of adjustability.

With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

In the drawing:

Figure 1 is a side elevation of the brace showing the same applied to the pipe.

Figure 2 is a vertical transverse sectional view taken on line 2—2 of Figure 1.

Figure 3 is a horizontal sectional view taken on line 3—3 of Figure 1.

Referring to the drawing the numeral 1 designates an L, and 2 a second L which is in a reverse relation to the L 1. The L's are telescopically engaged at 3, thereby forming a horizontal portion 4 and the L's have their branches 5 and 6 vertically disposed. Connected to the upper end of the L branch 5 is a pipe section 7 which extends into a discharge opening 8 in a ceiling 9 for discharging products of combustion to the atmosphere. The pipe 10 is connected to the lower end of the L branch 6 and which pipe 10 is adapted to lead to a stove.

It has been found that when it is necessary to remove a stove for any reason, the ceiling connection and L connections are broken, con-

sequently soot and other objectionable dirt drops to the floor. To obviate the above difficulty a vertically disposed bar 11 is provided, which bar 11 is anchored at 12 to the ceiling 9 and extends downwardly and is provided with a segmentally shaped portion 13, which engages one side of the horizontal portion 4 of the L 2. Secured by means of bolts 14 to the other side of the branch 8 of the L is a segmentally shaped member 15, and it will be seen that the branch 4 is positively clamped between the members 13 and 15, consequently said branch will be maintained in its relative relation to the ceiling at all times. The lower end of the bar 11 terminates below the horizontal portions of the L's and has connected thereto by means of a bolt 15 an arm 16 which terminates in a clamping loop 17, which extends around the pipe 10 and rigidly holds the same, therefore it will be seen that the pipe 10 is rigidly held in relation to the L's 2 at all times. Secured to the bar 11 by means of a bolt 18 at a point above the branch 4 is a horizontally disposed arm 19, which arm 80 terminates in a clamping loop 20, which encircles the pipe section 7, therefore it will be seen that the pipe section 7 will be rigidly braced in relation to the L 1 and that the upper end of the pipe 7 will be maintained in 85 the discharge opening 8 at all times. Bolts 15 and 18 extend through elongated openings 21 in the bar 11, thereby allowing a range of adjustability and the bolts 14 and 22 of the clamping members 17 and 20 also extend 90 through elongated apertures for allowing said clamping members to be adjusted for variations in diameters of parts they encircle, therefore it will be seen that the device may be easily and quickly adjusted to various sizes 95 of pipes and L's, and the device may be applied without varying the structure.

From the above it will be seen that a brace is provided for stove pipes and the like which is simple in construction, the parts reduced 100 to a minimum, and one which may be cheaply manufactured and sold. It will also be seen that the device may be used in connection with various kinds of pipes, and one of the loops may be eliminated if desired.

The invention having been set forth what is claimed as new and useful is:—

A support for the discharge end of a stove pipe discharging through an opening in a ceiling, said discharge end comprising a vertical portion, a horizontal portion, a second vertical portion, said support comprising a

bar anchored to the ceiling and extending downwardly, a segmentally shaped portion carried by said bar and engaging one side of the horizontal portion of the pipe, a segmentally shaped member engaging the other side of the horizontal portion of the pipe and detachably connected to the bar above and below the horizontal portion of the pipe, a looped member connected to the bar above

the horizontal portion of the pipe and 10 clamped around the vertical portion of the pipe and a looped member connected to the bar below the horizontal portion of the pipe and clamped around the second vertical portion of the pipe.

In testimony whereof I hereunto affix my signature.

RALPH WILLIS LIVINGSTON.
